UNITED STATES PATENT OFFICE

CARL E. BISHOP, OF MITCHELLVILLE, IOWA

STEAM GENERATOR AND METHOD OF GENERATION

Application filed April 14, 1930. Serial No. 444,248.

My invention has to do with steam generators of the kind adapted for use with motor vehicles, aeroplanes and the like.

The object of my invention is to provide such a steam generator which may be compactly built and is of simple, durable and inexpensive construction.

More particularly, it is my object to provide such a steam generator of novel construction having a water cage and a plurality of steam sections and a steam chest section in which all of the connections are at the top of the generator and away from the burner below the generator.

Another object is to provide such a generator in which the connections are provided with joints so arranged as to permit them to be disconnected for lifting out any of the sections.

Another purpose of the present invention is to provide a generator of the kind mentioned in which there is a water cage comprising a series of upright tubular elements preferably arranged in a circle and having a sediment ring arranged in portions inclined from the horizontal for receiving sediment and facilitating the ready removal thereof.

Still a further object is to provide such a water cage with coils, each connected with the lower part of one of the tubular elements and preferably wound around one of the steam sections and then connected with another of the tubular elements to insure circulation of water around the water edge.

Another object is to provide a method for generating steam for getting the maximum benefit of transmission of heat by convection.

With these and other objects in view, my invention consists in the construction, arrangement and combination of the various parts of my steam generator and method of generation, whereby the objects contemplated are attained, as hereinafter more fully set forth, pointed out in my claims, and illustrated in the accompanying drawings, in which:

Figure 1 shows a top or plan view of a steam generator embodying my invention.

Figure 2 shows a side elevation of the same, parts being broken away.

Figure 3 shows a vertical, detail, sectional view taken on the line 3—3 of Figure 1, parts being broken away; and

Figure 4 shows a vertical sectional view through the steam chest section of a modified form of my invention.

My improved steam generator, generally speaking, consists of a water cage indicated by the reference character A and having generally a circular form around the outside of the device, a plurality of steam sections arranged within the water cage, each being indicated by the reference character B, and a steam chest section at the center of the generator indicated by the character C.

In the use of the generator, the water is taken from the water cage and carried through coils wound around the respective steam sections and heated, and the steam and water from the coils are reconducted to the water cage. Then the steam is conducted from the water cage to the respective steam sections and from thence to the steam chest section.

The water cage A consists of a plurality of upright tubular water containers 10, preferably arranged in a circle around the outside of the generator. These water containers 10 are connected at their lower ends by a sediment ring indicated generally at D, which extends around the bottom of the water cage and comprises a series of portions 12 successively connecting the water containers 10 and arranged at angles to the horizontal in saw-tooth fashion.

The water containers 10 are of different lengths as shown.

Each section 12 extends as it were in both directions from one of the longer and one of the shorter containers 10, as indicated in Figure 2, and projects downwardly slightly from the longer container 10 and upwardly slightly from the shorter container 10 as shown in that figure.

Each portion 12 thus provides in effect a substantially straight tube communicating with two of the water containers 10.

The lower end of each portion 12 of the

sediment ring D has a clean-out plug 14, which may be removed for cleaning out sediment in the ring.

Each water container 10 has near its lower part a blow-out valve 16, which may be opened for blowing out the sediment by boiler pressure, thereby providing a means for cleaning the generator while in operation.

The purposes and advantages of this saw-tooth shape of the sediment ring will hereinafter be more fully referred to.

The upper ends of all the water containers 10 are preferably connected by an annular tubular head member 18, which communicates with each of the containers 10. The diameter and height of the containers 10 may be varied somewhat according to the purpose of the generator and the size desired.

A plurality of steam sections B are arranged inside the water cage A. Each of the sections B comprises an upright tubular member as illustrated in Figure 3, having an upper portion 20, below which is a somewhat reduced portion 21, around which the coil is wound, and a lower reduced end 22 with a thickened very strong wall 23.

There is provided a heating coil for each steam section B. For indicating a coil, I have used the character F.

Each coil F is preferably composed of two coils, one of which will now be described.

Each member of each complete coil includes a lower portion 24 communicating with the lower part of one of the water containers 10 and inclined upwardly therefrom and wound around the reduced portion 21 of one of the steam sections B, as at 26, (Figure 2), and then inclined upwardly therefrom to the upper portion of another one of the containers 10, as at 28.

The other member of each coil is the same as that already described, and arranged parallel therewith, the parts being indicated by the reference numerals 24a, 26a, and 28a.

In Figure 1 the upper member of one of the coils is indicated at F, and the upper end of a coil going to one of the inner steam sections is indicated at F'.

It will be understood that below the steam sections is a suitable burner 30. (Figure 3.)

One of the objects of the present invention is to provide connections at the top of the steam sections only, so that they will not be subjected to the intense heat from the burner 30, and another object is to so arrange those connections that they may be loosened at the top of the device in such manner as to lift out any particular steam section.

Thus for each of the outer steam sections B a tube 32 is welded into the top of the steam section (see Figure 1).

Similarly for each of the inner steam sections B, a similar tube 32a is welded into the

top of the inner steam section (see Figures 1 and 3).

Each of the tubes 32 and 32a is connected with the upper part of the water cage as for example with the member 18 by means of a disconnectable union 34.

It follows that so far as the connection between the steam section B and the water cage is concerned, the union 34 may be disconnected and the steam section B with its tube 32 or 32a as the case may be may be lifted upwardly out of the assembly.

A means should be provided for insuring that the steam conducted from the water cage to the steam section B will travel to the bottom of the steam section from the tubes 32 and 32a before traveling up and out of the steam section.

This may be accomplished in various ways but as here illustrated a tube 36 is extended through the top of the steam section B, as shown for instance in Figure 3, and is screwed into the top of said steam section and extends downwardly to the lower interior of the section whereby it causes the steam to travel substantially double the length of the steam section.

A tube 38 (see Figures 1 and 2) has the branches 38a, 38b and 38c connected with the respective steam sections B by means of disconnectable unions 34, such as that already described.

The inner end of each tube 38 connects with the steam chest section C by means of a disconnectable union 34 of the kind mentioned.

Thus by disconnecting the proper unions 34, any one of the steam sections B may be conveniently lifted out. For instance, any steam section may be taken out by disconnecting the unions 34 of the pipe 38 and the branches thereof, and by disconnecting the unions 34 of the particular tube 32 or 32a connected with the steam section B to be removed.

I shall now describe the steam chest section. I have shown this in two forms in Figures 3 and 4, and will first describe the form disclosed in Figure 3.

In this particular form of steam chest section, there is provided a central, upright, tubular casing 40 with a reduced lower end 40a, having thickened walls 40b.

Surrounding the casing 40 is a series of upright tubes 42, each connected at its upper end by means of one of the unions 34 with the inner end of one of the tubes 38.

At the lower end of each tube 42 is a reduced portion 44 inclined downwardly and communicating with the reduced lower end 40a of the casing 40 and welded thereto.

Thus the steam supplied by the steam chest must travel to the lower part thereof and thence upwardly through the casing 40. From the upper part of the casing 40 leads a

steam conducting pipe 46 connected with the top of the casing 40 by means of a disconnectable union 34.

It follows that by disconnecting the proper unions 34 the steam chest C may be lifted bodily out of the assembly.

In Figure 4 is another form of steam chest section comprising an outer casing or tank 48 with a thickened bottom 48a. An inner tank 10 or casing 50 is welded to the top of the tank 48, as shown in Figure 4, and projects downwardly to the lower interior of the tank 48, and is provided with a passage 52 in its lower end.

15 In the form of steam chest section shown in Figure 4, the tubes 38 are connected with the top of the tank member 48 by means of unions 34, as shown, and the take-off pipe 46 is similarly connected with the top of the tank 50 by 20 means of a disconnectable union 34.

The form of steam chest section shown in Figure 4 is indicated generally by the reference character C'.

Having now described the structure of my 25 improved steam generator, I shall refer briefly to the manner of using it and to some of its advantages.

Water is supplied to the water cage A in any suitable way. It should perhaps be mentioned at this point that I preferably employ 30 in connection with a generator of this kind a condenser by which the water of condensation from the steam, after the steam is used, is returned to the generator.

35 When the burner is operating, the coils and the steam sections and steam chest section will be very rapidly heated. I use double coil members 24 and 24a in order to give the water and steam a more rapid rise for more quickly 40 generating steam.

This rapid circulation set up by the heat of the burner and the coil construction prevent sediment, lime and the like, from lodging or collecting in the coils and carries it into the water tubes where it settles to the sediment ring 12.

The advantage of the construction and this means of rapid circulation make possible the use of small diameter tubing in the coils thereby increasing the speed of steam generation through a more thorough application of heat to the water.

The heat causes the water and steam to travel upwardly through the coils F and to emerge into another container 10, whereupon the water drops down and the steam rises to the top of the container and then passes through one of the tubes 32 or 32a to one of the steam sections B.

In the steam section B, the steam travels to the reduced lower end 22 thereof where it is again subject to the direct heat of the burner around the thickened portion 23, and thence upwardly through one of the tubes 36 and through one of the tubes 38 and one of its

branches to the steam chest section in which the steam is again carried to the bottom of the steam chest section and superheated and conducted away through the tube 46.

It has been noted that the water which passes through the coil passes from one water container 10 to another around the circle, so that there is thus caused a circulation of water around the water cage.

The generator is preferably used with the 75 level of the water in the containers 10 just below the inlet upper ends of the coils.

By the structure here shown, there is caused a constant and gradual downward movement 80 of the large volume of water in the containers 10, so that all sediment naturally settles at the bottom where it can be readily cleaned out from the sediment ring.

It will be noted that the sediment ring is outside the burner, so that it does not become 85 unduly hot.

The burner is preferably located above the lower parts of the sediment ring, so that the sediment can settle below the burner level and will not become burned and caked to 90 the wall of the sediment ring.

Other advantages have already been referred to and generally it is obvious that with a structure of this type, the steam can be generated with great rapidity and the 95 heating increases until the steam reaches the steam chest section, where it is superheated for use in an engine for a motor car, aeroplane or the like.

The construction is really very simple and 100 is such that the steam chest section or any steam chest may be very easily removed for purposes of repair or replacement.

The construction whereby rapid movement 105 through the coils, and movement of water around the water cage, are secured, enables me to get the maximum benefit of transmission of heat by convection.

The arrangement of the water containers in the form to hold vertical columns of water, allows the weight of the columns to force water into the coils. The use of small coils with sharp rises makes it possible to heat the water and turn it to steam, with great rapidity.

110 The construction whereby the steam and water are separated as they emerge from the coils contributes to rapid generation. The water level is high, but below the coil outlets. The temperature at the upper ends of the coils can be much higher than if the water level were at that height.

115 Changes may be made in the details of the construction and arrangement of the parts of my improved generator without departing from the real spirit and purpose of my invention, and I intend to cover by my claims any modified forms of structure 120 or use of mechanical equivalents, which may 125 130

be reasonably included within their scope.

I claim as my invention:—

1. In a steam generator, the combination of a water cage, a plurality of steam sections, coils communicating with the water cage and coiled around the steam sections and leading to the upper portion of the water cage, means for conveying steam from the upper parts of the water cage to the upper parts of the steam sections including separable joints, and means for conducting steam from the steam sections, emerging from their upper parts and including separable joints, whereby a construction is secured having no connections at the bottoms of the steam sections, said joints being so arranged that when they are disconnected the steam sections may be separately lifted out of the assembly.
2. In a steam generator, the combination of a water cage, a plurality of steam sections, coils communicating with the water cage and coiled around the steam sections and leading to the upper portion of the water cage, means for conveying steam from the upper parts of the water cage to the upper parts of the steam sections including separable joints, and means for conducting steam from the lower interiors of the steam sections and emerging from their upper parts and including separable joints, whereby a construction is secured having no connections at the bottoms of the steam sections, said joints being so arranged that when they are disconnected the steam sections may be separately lifted out of the assembly.
3. In a steam generator, the combination of a water cage, a plurality of steam sections, coils communicating with the water cage and coiled around the steam sections and leading to the upper portion of the water cage, means for conveying steam from the upper parts of the water cage to the upper parts of the steam sections including separable joints, and means for conducting steam from the steam sections, emerging from their upper parts and including separable joints, said steam sections being provided with means for causing the steam to travel substantially double the entire lengths thereof, whereby a construction is secured having no connections at the bottoms of the steam sections, said joints being so arranged that when they are disconnected the steam sections may be separately lifted out of the assembly.
4. In a steam generator, the combination of a water cage, a plurality of steam sections, coils communicating with the water cage and coiled around the steam sections and leading to the upper portion of the water cage, means for conveying steam from the upper parts of the water cage to the upper parts of the steam sections including separable joints, and means for conducting steam from the steam sections, emerging from their upper parts and including separable joints,

said steam sections being enlarged above the portions surrounded by the coils, whereby a construction is secured having no connections at the bottoms of the steam sections, said joints being so arranged that when they are disconnected the steam sections may be separately lifted out of the assembly.

5. In a steam generator, the combination of a water cage, a plurality of steam sections, coils communicating with the water cage and coiled around the steam sections and leading to the upper portion of the water cage, means for conveying steam from the upper parts of the water cage to the upper parts of the steam sections including separable joints, and means for conducting steam from the steam sections, emerging from their upper parts and including separable joints, said steam sections being reduced in size at their lower ends and having means for causing the steam to travel through such reduced lower ends, whereby a construction is secured having no connections at the bottoms of the steam sections, said joints being so arranged that when they are disconnected the steam sections may be separately lifted out of the assembly.

6. In a steam generator, a burner, a vertical steam section, having a reduced lower end exposed to the direct head of the burner, and having means for conducting steam into and from the upper end of the section and causing the steam to travel to the reduced lower end.

7. In a steam generator, a plurality of steam sections, a steam chest section, means for conducting steam from said steam sections to the upper part of the steam chest section, including separable joints, means for conducting steam from the steam chest section connected with the upper part thereof, having separable joints, said joints being arranged to permit their disconnection so that the steam chest section may be lifted out of the assembly, and a burner below said sections, said steam chest section having means for causing steam to travel substantially double the vertical length thereof.

8. In a steam generator, a plurality of steam sections, a steam chest section, means for conducting steam from the upper parts of said steam sections to the upper part of the steam chest section, including separable joints, means for conducting steam from the steam chest section, connected with the upper part thereof, having separable joints, said joints being arranged to permit their disconnection so that the steam chest section or any steam section may be lifted out of the assembly, and a burner below said sections.

9. In a steam generator, a burner, a vertical steam section directly exposed to the heat of said burner, means for supplying steam thereto at the upper part thereof, means for removing steam therefrom at the upper part thereof, one of said means including a conducting pipe extending nearly to the bottom

of the steam section on its inside and having a threaded connection with the top of the steam section, so that it may be readily removed from the steam section.

5 10. In a steam generator of the kind described, an outer substantially annular water cage, a plurality of upright tubular steam sections within the water cage and a steam chest section at the center of the device, means for connecting the upper end of the water cage with the upper ends of the steam sections, means for connecting the upper ends of the steam sections with the upper end of the chest section, a sediment ring at the lower end of the water cage having its portions arranged in position inclined from the horizontal, and a burner under the central portion of the generator arranged above the level of the lower parts of the sediment ring.

20 11. In a steam generator, a water cage having a series of upright tubular elements, and a sediment ring connecting the lower ends of said elements, comprising alternate portions, inclined from the horizontal.

25 12. In a steam generator, a water cage having a series of upright tubular elements, and a sediment ring connecting the lower ends of said elements, comprising alternate portions, inclined from the horizontal, and having cleanout plugs at the lower ends of such portions.

30 13. In a steam generator, a water cage having a series of upright tubular circumferentially spaced elements, and a series of coils, 35 each connected at one end with an element at the extreme lower part thereof, and at the other end with another element at the extreme upper part thereof, whereby water will be caused to circulate from the bottom end of one element to the top end of another circumferentially spaced element.

40 14. A water cage for a steam generator comprising a plurality of upright water containers arranged substantially around a common center, a tubular head connecting the lower ends of all of the said containers, comprising a series of portions each inclined from the horizontal, having cleanout openings and closures therefor at their lower ends.

45 15. A method of generating steam comprising the heating of water in coils connected at their lower and upper ends respectively with the lower and upper ends of successive water containers arranged substantially around a common center, whereby the water is caused to travel through a series of said containers, heat being also applied to the containers.

50 Des Moines, Iowa, March 25, 1930.
CARL E. BISHOP.
